UNITED STATES PATENT OFFICE.

CHARLES E. PERRY, OF MILES CITY, MONTANA.

SEPARABLE BUTTON.

SPECIFICATION forming part of Letters Patent No. 468,037, dated February 2, 1892.

Application filed June 30, 1891. Serial No. 397,982. (No model.)

To all whom it may concern:

Be it known that I, CHARLES E. PERRY, a citizen of the United States, residing at Miles City, in the county of Custer and State of

5 Montana, have invented a new and useful Improvement in Separable Buttons, of which the following is a specification.

My invention relates to an improvement in separable buttons of the character set forth 10 and described in Letters Patent of the United States No. 434,802, granted to me August 19, 1890. The separable button as described and claimed in said Letters Patent involves two parts—a head-piece and the button proper— 15 having a tapering shank adapted to enter a concentric tubular extension of the head-piece and retained by a spring locking-shoulder to be displaced by a wedge-shaped disk, the operation of which, when pressed by 20 the finger, is to spread the spring locking-shoulders to permit the button to be withdrawn. The construction shown in that patent is entirely operative and presents many points of desirability; but I have found that 25 the same is capable of improvement, whereby it may be manufactured more economically in the quantity necessary to supply the demand; and the object of my present invention is to effect this improvement in the manner presently described.

My invention consists in the separable button comprising, as before, the hollow head-piece, disk-shaped in plan view and having a short concentric tubular extension in its 35 lower side or collet, perforated centrally in its upper face-plate and carrying in its interior a circular locking device comprising segments adjusted together and held in place by a surrounding spring. A wedge or button 40 tapering in its lower part is retained in the central aperture afforded in the locking device and projects through the central perforation in the face-plate, and its operation under the pressure of the finger is to spread apart the segments forming the locking device against the resistance of the retaining-spring. The button is provided, as in the 45 case of the patent above mentioned, with a concentric shank, the extremity of which is 50 provided with an annular shoulder adapted to be engaged by the locking device when in its normal position under action of its spring.

The operation of inserting and withdrawing the button, so far as the manipulation is concerned, is the same as in the case of my previous Letters Patent.

In the drawings, Figure 1 is a horizontal central section through the head-piece. Fig. 2 is a sectional elevation of a button with all the parts adjusted together; and Figs. 3 and 4 are plan views, respectively, of the face-plate and collet.

A represents the button provided with the concentric shank B, having its inner end reduced and provided with a shoulder t. Instead of the form shown in the present drawings, the shank may have the form illustrated in my said Letters Patent, according to the preference of the manufacturer. The head-piece comprises, preferably, a centrally-perforated face or top plate C, turned over at the edge to form a flange s, and a centrally-perforated collet D, turned up at its edge to form the flange s', adapted to fit closely within the flange s, and it is provided by preference 75 with an integral concentric projecting tubular extension r of a dimension sufficient to receive the shank of the button. Supported between the face-plate and collet of the head-piece, but not necessarily fixed therein, is the 80 locking-plate E, comprising segments p, held normally together by the surrounding spring F. Each segment is provided on its inner edge with the upward extension o, the lower extremity of which affords a shoulder, while 85 the outer end of the extension tapers to produce, when the segments are adjusted together, a wedge-shaped opening. The dimension of the aperture obtained in the plate E, when the segments are adjusted and held together, is such as to provide a shoulder to act 90 against the shoulder t, formed upon the shank of the button, thus serving to hold the button against withdrawal after the same has been introduced. A push-button G, preferably 95 made hollow and at its lower edge enlarged into a flange n, as shown, is inserted from below through the central aperture in the face-plate C and rests normally in the upper part 100 of the tapering or wedge-shaped opening between the flanges o, formed in the locking-plate E.

The operation of the device is as follows: The push-button G having been introduced

into its aperture, the locking-plate segments adjusted together within the spring F and introduced between the face-plate C and collet D, the face-plate and collet may be soldered 5 or otherwise secured firmly together. The shank B is thereupon introduced through the tube r until its shoulder is caught in the shoulder formed in the locking-plate, the segments of the latter being separated against 10 the resistance of the spring during the introduction of the shank, and the button is thereupon complete and the parts irremovable, except upon a positive action exerted against the push-button G. The effect of pressure 15 against the push-button is to cause an expanding of the locking-plate, releasing the shank and permitting the button to be withdrawn.

The locking-plate may be made in as many 20 segments as may be desired, whether formed as segments of the same plate radially divided or as separate pieces, and the spring may assume other forms than that shown. The push-button may be varied in its construction, as mentioned in my previous Letters Patent, and the head-piece may be made of a single piece of metal or several pieces, according to the election of the manufacturer.

It is deemed unnecessary to recite the various 25 modifications which are possible; but I desire it understood that such variations as I have mentioned and others of a similar

character not departing from the principle of the invention as covered by my claims are intended to be included therein.

What I claim as new, and desire to secure by Letters Patent, is—

1. A separable button comprising, in combination, a button A, having a shouldered shank, a hollow head-piece perforated for the reception of the shank, a locking-plate within the head-piece, comprising radially-extending spring-controlled sections p and having the central annular shoulder, and a wedge engaging and expanding the locking-plate, substantially as described. 45

2. A separable button comprising, in combination, a button A, having a shouldered shank B, the hollow head-piece C D, having central perforations opposite to each other, a locking-plate E, composed of segments p, held together by a surrounding spring F and presenting the tapering central opening terminating in a shoulder adapted to engage the shoulder on the shank, and a push-button entering the tapering aperture of the locking-plate and extending through the central opening in the upper face-plate of the head-piece, the parts being arranged to operate substantially as described. 55

CHARLES E. PERRY.
